RAILWAY CAR JOURNAL FAILURE DETECTOR AND WARNING DEVICE

Athol B. Clark, 521 W. 8th Ave., Amarillo, Tex., and
Richard K. Delaney, 401 Ave. F SE., Childress, Tex.

Filed Aug. 4, 1958, Ser. No. 753,054

7 Claims. (Cl. 246—169)

This invention relates generally to railway rolling stock and is directed particularly to a new and novel device for detecting possible failure of journals.

The wheel journals of railroad freight and passenger cars sometimes fail through causes which are not always known, and such failures, when they occur, inevitably result in the overheating of the journal, and if not detected in time, the result is overheating to the extent of melting the babbitt of the bearings and the damaging of other materials resulting in a breakdown which if not detected will lead to the wrecking of the train and possibly fire.

The present invention accordingly has for a principal object to provide a simple, dependable, durable and economical device for preventing wrecks and resulting property damage and possible loss of life resulting from failures of car wheel journals.

Another object of the invention is to provide a device for accomplishing the foregoing object, which can be readily connected with the pneumatic brake system which is standard on all railroads in this and other countries and which when made operative as a result of heating of a journal, will bring about the application of the car brakes.

Still another object of the invention is to provide a device of the character stated which is devoid of metallic contact working surfaces whereby the possibility of moving parts jamming or sticking from rust or corrosion during periods of disuse will be avoided and the mechanism or parts of the device will be immediately activated or put in condition for use each time the car is connected into the train air brake line.

Still another object of the invention is to provide a device of the character stated which is so designed that after being once installed will never require maintenance or attention unless and until it should be made to operate as a result of the overheating of a wheel journal and which, in such event, is easily and quickly restored to its original condition ready for further operation if and when such operation should become necessary.

A still further object of the invention is to provide in a device of the character stated a thermal element designed to be mounted inside the journal box in close proximity to the journal shaft whereby to absorb heat by radiation as well as by conduction through parts in metallic contact with the journal box wall and which element, upon such absorption of heat, will effect the momentary lowering of the air pressure in the brake system to bring about the application of the car brakes.

The invention will be best understood from a consideration of the following detail description taken in connection with the accompanying drawings forming part of the specification, with the understanding, however, that the invention is not confined to a strict conformity with the showing of the drawings but may be changed or modified so long as such changes or modifications mark no material departure from the salient features of the invention as expressed in the appended claims.

2

In the drawings:

Fig. 1 is a view in side elevation of one of the usual two-wheel trucks of a railway freight or passenger car showing two wheels on one side of the truck and illustrating the application of the present invention to the journal boxes which are shown open;

Fig. 2 is a view on an enlarged scale, partly in section and partly in elevation, of the air release valve showing the diaphragm seated for maintaining the air pressure in the air line leading to the thermal elements;

Fig. 3 is a view corresponding to Fig. 2, but showing the valve diaphragm unseated for effecting the reduction of air pressure in the train air brake line;

Fig. 4 is a view partly in section and partly in elevation of a journal box showing the same open and showing the thermal blow-out element mounted therein;

Fig. 5 illustrates in section a type of adjustable valve which may be used in connection with the present invention.

Referring now more particularly to the drawings, it will be understood that the car truck structure illustrated in side elevation in Fig. 1 is only sufficiently diagrammatically shown to illustrate the application of the present invention to two journal boxes. Also it will be understood that while only two journal boxes are shown, the device will be connected with the journal boxes of the opposite pair of wheels of the illustrated truck and to the journal boxes of all of the other wheels on the car. As hereinbefore stated, the invention is designed to be used in connection with the pneumatic brake system which is standard on substantially all railroads and which is generally known as the "Westinghouse Brake System" and, as is well known, such a system consists of interconnected air pressure lines maintained by a compressor on the train engine and extending the entire length of the train and in this system the wheel brakes, not illustrated, are held in release by the air pressure and the release of such air pressure effects the automatic spring operated application of the brakes for controlling the speed of or stopping the train.

In Fig. 1, the numeral 10 generally designates a portion of a car body while the numeral 12 generally designates a wheel truck. This wheel truck usually embodies four wheels, two only of which are here shown, and which are designated 14, and the truck frame 16 is supported upon the wheel journals 18 upon which bear or rest bearings 20.

Each wheel journal extends into the journal box 21 which embodies the side walls 22, the top 23, and a lower portion 24 which is conventionally designed to house a lubricant or mechanism for applying a lubricant to the journal. The outer side of each journal box is open and is normally covered by a door or lid 25 which in Fig. 1 is shown raised or in open position for each of the illustrated boxes.

The other parts of the wheel truck and the manner in which the car body is supported on the truck are well known, and as they have no bearing upon the present invention, further illustration of such parts is not considered necessary to an understanding of the invention.

The numeral 26 designates a portion of the train compressed air pipeline by which air under pressure is conveyed to the brake control apparatus of the different cars of the train and, as previously stated and as is well known, upon the reduction of pressure in this pipeline the train brakes, not shown, become applied to the wheels 14, and the present invention is designed to bring about such a reduction of air pressure in the pipeline 26 in the event of a wheel journal overheating.

In accordance with the present invention there is provided a coupling 27 in the air brake line 26 which has a lateral arm 28 with which is connected a nipple 29 lead-

ing to one side of a manual valve which is generally designated 30 and which is here shown as being of the rotary plug type. The body of the valve is designated 31 and the plug is turned by the usual handle 32.

Connected with the valve 30 is a pressure operated diaphragm release valve which is generally designated 33. This release valve embodies a housing made up of the two conical or frusto-conical shell portions 34 and 35 disposed in base-to-base relation and having interposed between them the flexible diaphragm 36 constructed of suitable material, such as rubber and fabric or other impervious flexible material which will permit the diaphragm to flex in the operation of the valve.

The upper half 34 of the diaphragm valve housing has its apex portion extended to form the collar 37 and the manual valve 30 has its body 31 connected on the opposite side from the nipple 29, with the pipe 38 which passes through and is joined to the collar 37 and terminates within the diaphragm valve housing adjacent to the upper surface of the diaphragm 36. The inner end of the pipe 38 forms a seat 39 against which the diaphragm 36 bears when the diaphragm valve is closed. When the diaphragm is in this closed position it will be flat and lie in one plane with the top surface contacting the inner end of the pipe as stated and the diaphragm maintains its position by its own inherent resiliency which causes it to return to the flat condition shown.

The wall of the conical shell 34 is provided with a number of openings 40 by which air from the air pipe line may escape to the atmosphere when the diaphragm is unseated for the purpose hereinafter set forth, and the base portion of the part 34 is defined by the outwardly projecting annular flange 41.

As stated, the diaphragm is of flexible material such as rubber and bears against the seat 39 when it is closed or when it is in valve closed position. Consequently, upon the application of air pressure through the pipe 38 against the flexible diaphragm the latter will yield and become unseated to open the valve. When such pressure is removed, the flexible diaphragm will be returned to its seated position against the inner end of the pipe 38, which position is the valve closed position.

The lower conical portion 35 of the diaphragm housing also is defined around its base by the flat annular flange 42 while the apex portion thereof is extended to form a tube or nipple 43 for connection in the lateral arm portion 44 of a T-coupling 45.

As shown, the diaphragm 36 is secured around its peripheral portion between the opposed flanges 41 and 42 and the three parts consisting of the shell portions 34 and 35 and the diaphragm 36 are firmly clamped together by suitable bolts 46.

The diaphragm in its central portion has means for passing air through from one side of the diaphragm to the other, which means comprises a tube 47 having a bleed orifice or passage 48 longitudinally therethrough as compared to the pipe 38, and this tube which may be of approximately $\frac{1}{16}$ " diameter is formed integral with a plate 49 which is embedded in the body of the diaphragm 36. As shown, the plate 49 is adjacent to one end of the tube 47 and the plate is set in the diaphragm so that a major portion of the length of the tube projects above the diaphragm into the pipe 38 while the shorter portion extends downwardly into the housing shell 35.

Connected with the oppositely directed arms 50 of the T-coupling 45 are tubes 51 and 52. As illustrated in Fig. 1, the tube 51 leads to thermal units 53 in one pair of journal boxes 21. The other tube 52 extends to the opposite end of the car and is connected to a similar pair of thermal units, not shown, carried by journal boxes at such end of the car and the tube 52 may be conveniently attached for support to the air line pipe 26 by suitable bands 54 or in any other manner, or it may be mounted on the body of the car or otherwise supported as may be desired.

As previously stated, each and every one of the journal boxes 21 of a car will be equipped with one of the thermal units 53. Therefore, although only two journal boxes are here illustrated, it will be understood that the other boxes will be similarly equipped and that the thermal units will be connected with the air line of the brake system in the same manner as illustrated in Fig. 1.

Each of the thermal units 53 embodies a flat head portion 55 which may be in the form of a disc or plate of any suitable geometrical form and from one side of this head extends the tubular stem 56 which through a portion of its length and from the free end thereof is internally and externally screw threaded as indicated at 57 and 58. This thermal unit is in the form of a casting of a metal such as aluminum, which is a good conductor of heat.

The tubular stem 56 is adapted to be extended through an opening 59 in a wall of the journal box, preferably the side wall, at a point where it will be nearest to the journal with the under side of the head positioned against the inner side of the journal box wall. The bore through the stem 56 is designated 60 and terminates within the central portion of the head 55 where it intersects and merges with a radial bore or passage 61. The passage or bore 61 is filled with a fusible material 62 having a melting point substantially above the maximum normal operating temperature of the journal and substantially below the melting point of the babbitt of the journal as, for example, around 400° F.

Each of the thermal unit stems 56 has mounted thereon the securing nut 63 which bears against the outer surface of the journal box wall and draws the head 55 tightly into position against the inner side of the wall, as shown.

The air tube 51 is connected by a three-way coupling 64 with the two distributor tubes 65. Each of these distributor tubes 65 is connected by a coupling 66 with an end of a coupling nipple 67. The other end of this nipple is threaded, as illustrated, at 68 and introduced into the end of the stem of the adjacent thermal unit and joined thereto by engagement with the threads 57.

Any suitable means may be employed for supporting the tubes 51 and 65 on the truck frame so that there will be no movement or vibration which will tend to weaken the joints or cause breakage of the tubes. The coupling 66 connecting the outer end of each distributor tube 65 with the thermal unit 53 is of a conventional type commonly employed for joining together small bore tubes and accordingly it is not believed that detailed illustration and description of this coupling is required. The coupling 66 is, of course, provided so as to facilitate the easy removal and replacement of the thermal unit 53 when the fusible element has become fused or melted as a result of overheating of the wheel journal.

In putting the journal failure eliminator mechanism into service, the valve 30 is opened, after the air line of the brake system has been charged with air under pressure, to permit the air to pass through the orifice 48 of the diaphragm valve and be distributed by means of the tubes 51, 52 and 65 to the several thermal units. The air under pressure will then bleed through the diaphragm by way of the orifice 48 and establish pressure in the distributor tubes 65 against the fusible element 62.

Alternatively, the valves 30 may be left open at all times and then when the air brake lines of the individual cars are coupled together and the air under pressure introduced thereto, the mechanism will immediately activate for a few second when this connection is established, until pressure is built up by the passage of air through the orifice in the manner described.

So long as the tubes 65 are maintained closed, equal pressures will be maintained on both sides of the diaphragm 36 and the diaphragm will be maintained pressed against the seat formed by the edge 39 of the tube 38 due to the larger surface area on the under side of the diaphragm than that of the tube opening 38 at the upper side thereof.

It is necessary that the over-all air passage through the tubes 65 be greater than the air passage provided by the orifice 48 so that when the fusible element or material 62 of the thermal unit melts and is blown out by the air under pressure in the tube or tubes 65 on the lower side of the diaphragm, this air can escape faster than it can be replenished through the orifice 48. This will allow the diaphragm 36 to flex away from the end edge 39 of the tube 38.

When a journal in any one of the boxes becomes overheated and the temperature builds up to the point where the fusible element of the thermal unit becomes fused, then the pressure in the tube 65 and in the bore 60 of the stem 56, against the inner side of the fusible element 62, will cause such element to be dislodged and blown out. This will permit a rapid drop of pressure in the tube 65 and on the under side of the diaphragm 36, causing the greater pressure on the upper side of the diaphragm to flex the latter away from the seat 39. The air from the air line of the brake system will then escape through the tube 38 and the openings 40 in the upper portion 34 of the diaphragm valve, causing the brake line pressure to drop to a sufficient degree to cause application of the train brakes.

The upper portion of the tubular stem 47 extends into the tube 38 a substantial distance or far enough to preclude the possibility of a jet stream vacuum being established upon the surface center of the upper side of the diaphragm during the air exhausting or blowing process following the melting of the fusible element 62 and thereby defeating the operation of the device by preventing the diaphragm from becoming unseated.

Following the blowing of a thermal unit, the manual valve 30 may be closed to stop the escape of air from the train line and so maintained until the overheated journal has been properly serviced and the ruptured thermal unit replaced.

With no change in the basic principal involved, the capacity of the system may be changed by altering or changing the structural size of the elements or by using an adjustable valve in place of the simple shut-off valve 30 here illustrated, for either an emergency stop or for a less severe application of the brakes which would probably warn the engineer of impending trouble.

Another advantage in the use of the diaphragm valve is that it makes possible employment of air lines of materially smaller size than the conventional brake lines, such as air lines of from $\frac{1}{4}$ " to $\frac{1}{8}$ ", running to the journals and the fusible elements, thereby reducing the initial cost of installation and also providing for a more durable structure which will withstand vibration of the truck parts during operation.

In the illustration of the present invention, the standard type of freight car journal is illustrated but it will be readily apparent that the invention can be easily adapted to use with any type of journal.

From the foregoing, it will be seen that there is provided by the present invention a journal protective device and failure eliminator which is of relatively simple design and which can be economically produced and installed on cars of all types and which also is so designed that it can be so mounted as to be strong and durable and which will operate efficiently for accomplishing the desired results.

As above stated, there may be used in place of the simple rotary plug valve shown in Figs. 2 and 3, an adjustable valve such as that illustrated in Fig. 5. Such an adjustable valve is particularly well suited for use during experimental operation of the system.

In this Fig. 5, the adjustable valve shown comprises a body of substantially elliptical form which is generally designated 100 and which, at the opposite ends corresponding to the ends of the long axis of the ellipse, there are formed the threaded inlet and outlet openings 101 and 102 respectively. Perpendicular to the axis of the

5
10
15

aligned openings 101 and 102 the body 100 has formed integral therewith the neck 103 which has external screw threads 104 formed therearound and the interior of this neck 103 is provided with the coarse threads 105 which lead into the valve chamber 106.

The inner end of the valve chamber is reduced or tapered to form a seat 107 and the threaded inlet 101 communicates with the chamber 106 through the annular seat 107 by way of the passage 108 while at the opposite side of the seat the chamber 106 communicates with the threaded outlet opening 102 by way of the passage 109.

Extending axially in the chamber 106 is the cylindrical valve body 110 the outer end portion of which carries the screw threads 111 for engagement with the threads 105 and this outer end of the body 110 is connected on its long axis with the stem 112.

Threaded over the outer end of the neck 103 is the conventional cap 113 which has a suitable central opening 114 surrounded by packing 115 for the extension of the stem 112, the outer end of which carries the hand wheel 116.

The inner end of the valve body 110 carries a valve washer 117 which is adapted for engagement on the seat 107 in an obvious manner and it will be seen that when this valve is connected between the lateral arm 28 of the coupling 27, and the pipe 38, the flow of air from the brake line 26 to and through the diaphragm valve can be very nicely or finely adjusted, as may be required.

In the illustration of the valve 30 in Figs. 2 and 3, the nipple 29 and the pipe 38 have been shown formed integral with the body 31 of the valve, but these parts may be provided as separate couplings or nipples, as indicated at 29^a and 38^a.

We claim:

35. 1. A car journal failure detector and warning device comprising a thermal unit adapted to be mounted in a journal box and including a fusible element closing an air outlet port, a conduit for conducting air under pressure from an air brake pipe line to said port, and means 40 in said conduit for effecting a quick pressure drop in the air brake pipe line upon rupture of said fusible element comprising a diaphragm valve having a bleed orifice for passing air from said pipe line to the port side of the diaphragm whereby air pressure is balanced on both 45 sides of the diaphragm when the air outlet port is closed, and means whereby said diaphragm is maintained in valve closed position while said port is closed and permits the diaphragm to be moved to valve open position by air pressure from the pipe line upon the opening of said 50 port.

2. A car journal failure detector and warning device comprising the combination with an air brake line, of a diaphragm valve comprising opposite casing halves and a diaphragm between the same, an air admission pipe 55 connected with said air brake line and opening into one of said casing halves, a seat for the diaphragm whereby the diaphragm shuts off flow of air from the air brake line through said air admission pipe, the diaphragm being biased to constantly tend to move to seat engaging 60 shut off position, means for conveying air from the air brake line into the other valve casing half at a slower rate than its admission into said one half, whereby pressures are equalized on both sides of the diaphragm, a conduit of smaller diameter than said air admission pipe connected with and receiving air from said other casing half, and a fusible element closing the said smaller diameter conduit against escape of compressed air therefrom.

3. The invention according to claim 2, wherein the said means for closing the valve comprises an extension of said air admission pipe into said one casing half to a position whereby the inner end thereof forms the said seat for engagement by the diaphragm under the said biased tendency thereof and said one casing half having an air escape wall aperture.

4. The invention according to claim 2, wherein the

65
70

said means for conveying air from the air brake line into the other valve casing half comprises an orifice through the diaphragm of materially smaller diameter than said air admission pipe.

5. A car journal failure detector and warning device comprising the new combination with an air brake line, of a diaphragm valve which embodies two opposite casing halves and a diaphragm between the same, an air admission pipe connected with said air brake line and opening into one of said casing halves, means whereby the diaphragm closes the valve against exhaust of air from the air brake line through said air admission pipe, the diaphragm being biased to constantly tend to move to valve closing position, means for conveying air from the air brake line into the other valve casing half at a slower rate than its admission through said pipe into said one half, a conduit of smaller diameter than said air admission pipe connected with and receiving air from said other casing half, and a thermal unit adapted to be mounted within a journal box and comprising a stud having an enlarged head on one end and a passage therethrough, a fusible element closing said passage, and said stud being detachably connected at its other end with said conduit.

6. The invention according to claim 2, wherein the 25 said means for closing the valve comprises an extension of said air admission pipe into said one casing half for

5 engagement with and closure of its inner end by the diaphragm under said biased tendency thereof and said one casing half having an air escape wall aperture opening to the atmosphere, and the said means for conveying air from the air brake line into the other valve casing half comprises a small diameter orifice through the dia-

10 phragm.

7. The invention according to claim 2, wherein the said means for closing the valve comprises an extension of said air admission pipe into said one casing half for engagement with and closure of its inner end by the dia- 15 phragm under said biased tendency thereof and said one casing half having an air escape wall aperture opening to the atmosphere, and the said means for conveying air from the air brake line into said other valve casing half comprising a tube fixed in and through said dia- 20 phragm and extending for a substantial part of its length into said air admission pipe and having a bore of ma- terially smaller diameter than said pipe.
